UNITED STATES PATENT OFFICE.

FRANK S. FUJIWARA, OF VANCOUVER, BRITISH COLUMBIA, CANADA.

WRITING-PEN.

1,258,331.

Specification of Letters Patent.

Patented Mar. 5, 1918.

Application filed August 4, 1916. Serial No. 113,147.

To all whom it may concern:

Be it known that I, FRANK S. FUJIWARA, a subject of the Emperor of Japan, residing at Vancouver, in the Province of British Columbia and Dominion of Canada, have invented certain new and useful Improvements in Writing-Pens; and I do hereby declare the following to be a full, clear, and exact description of the invention, such as will 10 enable others skilled in the art to which it appertains to make and use the same.

The object of this invention is to increase the ink holding capacity of a writing pen point, by providing a simple, cheap, durable 15 and efficient attachment for the pen point that will take up a larger quantity of ink, at a single dipping of the pen point in an ink well.

Other objects will appear and be better 20 understood from that embodiment of my invention of which the following is a specification, reference being had to the accompanying drawing forming a part thereof in which:—

25 Figure 1 is a side view of a pen holder with the pen point associated therewith and showing the attachment applied to the pen point.

Fig. 2 is a top plan view of the pen point 30 detached from the holder and showing the attachment.

Fig. 3 is a bottom plan view of the pen point.

Referring to the drawing in detail, the 35 letter A designates a pen holder, and B a pen point carried thereby, the said pen point being of the usual construction, but in this particular instance having the sides thereof provided with recesses 1.

40 The attachment, for the pen point, is designated as an entirety by the numeral 2 and as shown more particularly in Fig. 2 is mounted on the upper side of the pen point, and includes an arcuate shaped head 3 that 45 engages over the upper side of the pen point,

at a point between the recesses 1 and has its opposite ends bent to provide clips 4 that are received by the recesses 1 and engage against the under face of the pen point, as shown in Fig. 3. The head 3 carries a stem 5, that 50 is of a width considerably less than the width of the pen point and has its free end pointed, as shown at 6 and spaced inwardly from the writing point of the pen. The stem 5 is curved longitudinally, as shown in Fig. 55 1 and provides a reservoir for receiving a quantity of ink, at the dipping of the pen point into an ink well, said stem 5 having an elongated opening 7 therein to facilitate the flow of ink from beneath the stem 5. 60

With a reservoir attachment constructed in the manner above described, a larger quantity of ink will be taken up, at a single dipping of the pen point in an ink well, thereby increasing the capacity of the pen 65 point and obviating numerous dippings thereof in an ink well, and also preventing blotting and evaporation of the ink.

Having thus described my invention what I claim as new is:—

A pen point attachment comprising a relatively large head arcuately curved to snugly fit the upper surface of the pen point and having its opposite sides bent inwardly toward each other to provide fastening elements to engage around and under the longitudinal edges of a pen point, and a reduced stem formed on said head and extending forwardly toward and into close proximity to the point of the pen, said stem being 80 curved longitudinally so as to engage the pen point at one place, and said stem having an elongated slot therein, as and for the purpose specified.

In testimony whereof I affix my signature 85 in presence of two witnesses.

FRANK S. FUJIWARA.
